UNITED STATES PATENT OFFICE.

HARVEY F. GASKILL, OF LOCKPORT, NEW YORK.

PUMPING-ENGINE.

SPECIFICATION forming part of Letters Patent No. 372,794, dated November 8, 1887.

Application filed April 14, 1887. Serial No. 234,737. (No model.)

To all whom it may concern:

Be it known that I, HARVEY F. GASKILL, of Lockport, in the county of Niagara and State of New York, have invented new and useful Improvements in Pumping and Similar Engines; of which the following is a specification.

My invention relates to pumping and other engines which act directly against a substantially uniform resistance, and in which steam is used expansively. Its object is to equalize the power of the engine—in other words, to compensate for the variation in power due to the decreasing pressure of the steam as it expands, and to do this by the action of the steam itself. This object I attain by causing steam under initial pressure to act against the motion of the engine during the first part of its stroke and to act with the motion of the engine during the last part of its stroke. In furtherance of this object I sometimes employ a receiver, into which the high-pressure steam is exhausted after doing its duty as above, and I cause steam from said receiver to act in opposition to the high-pressure steam—that is to say, to favor the motion of the engine during the first parts of its stroke and to oppose its motion during the latter parts of its stroke. I also draw steam from the receiver to drive the engine in some cases.

In the drawings I have represented a compound pumping-engine employing my invention. This engine consists of three cylinders, one of which is of larger diameter than the others, a receiver, into which the high-pressure steam is exhausted after doing its duty in the proper cylinders, and from which it is drawn off to do further duty under a lower pressure, and suitable valves for regulating the flow of the steam. The three cylinders are arranged in the same axial line, the larger cylinder being between the other two. Their pistons are all connected by suitable piston-rods and yokes, so that they all move together. High-pressure steam is admitted to the outer ends only of the small cylinders. The inner ends of those cylinders take steam from the receiver, and the larger cylinder is supplied direct from the inner ends of the small cylinders.

The operation of this engine may be best followed in connection with the drawings.

Figure 1 of the drawings is a top or plan

view. Fig. 2 is a longitudinal vertical section showing the pistons at the end of their travel and about to move in the direction indicated by the arrows and showing the position of the valves at that time. Fig. 3 is a similar section showing the pistons moved one-third of a stroke from the position in Fig. 2, this being the point of cut-off and corresponding positions of the valves. Fig. 4 is a similar section showing the stroke completed and the pistons about to start on the return-stroke. Fig. 5 is a similar section showing the position of the parts at the point of cut-off of the return-stroke, being one-third of that stroke. Figs. 6 and 7 show a convenient arrangement of this machine as a duplex pumping-engine.

A, C, and A' are the three cylinders; a, e, and a', their respective pistons; K, J, K', their respective piston-rods. The large cylinder C has two piston-rods, one at each side of the small cylinders.

I, I' are yokes connecting the piston-rods of the central cylinder with those of the end cylinders, so that all three pistons move together.

O is the continuation of the piston-rod system for operating the pump.

D and D' are the outer ends of the small cylinders; E and E', their inner ends.

F and F' are the two ends of the central cylinder.

d and d' are valves which govern the admission of steam to and its exhaustion from ends D and D', respectively.

e and e' are the valves which regulate the admission of steam to the ends E and E', respectively.

f and f' are the valves which regulate the passage of steam from E to F and from E' to F', respectively.

g and g' are the exhaust-valves of the central cylinder; P, the exhaust-pipe, which may lead to the condenser.

L is the main steam-pipe from the boiler; Q, the throttle-valve; l and l', the branches to convey steam from L to D and D'.

R is the receiver.

m, m', n, n' are pipes to establish communication of the receivers with D, D', E, and E', respectively.

The operation of the apparatus is as follows: Fig. 2 shows the pistons at the beginning of their stroke and the valves e, e', f, f', g, g' moving

in the direction indicated by the arrows. This motion of the valves closes e and opens e' , opens f and closes f' , closes g and opens g' , the valves d and d' meanwhile remaining in substantially the position shown. Steam accordingly enters D from receiver R through m and d and urges piston a forward. The steam in E from the previous stroke passes through f into F and urges piston e forward, and steam enters E' from receiver R through n' and e' and urges piston a' forward. The steam in F' from the previous stroke passes out through g' and P to the condenser, and steam from the boiler enters D' through l and d' . The three pistons are accordingly urged forward by steam under the pressure of the receiver acting in D and E' , and by steam in E and F acting expansively on the excess of area of C over a , and their motion is resisted by steam under boiler-pressure acting in D' and by the uniform resistance of the pumps. Acting under these forces, the pistons move forward to the point of cut-off shown in Fig. 3. At this point the valve e' begins to close, and is closed immediately thereafter, and the valves d and d' change their position, so that steam from the boiler is admitted through l and d into D , and the steam in D' is exhausted into the receiver R through d' and m' . The pistons are now urged forward by steam under boiler-pressure acting in D , by steam in E' acting expansively on a' , and by steam in E and F , as before, and their motion will be resisted by steam acting in D' under the pressure existing in the receiver, as D' is exhausting into the receiver, the valves being in the positions shown in Fig. 4, and also by the uniform resistance of the pumps. Acting under these forces, the pistons complete their stroke and reach the position shown in Fig. 4.

At this point the valves e , e' , f , f' , g , and g' move as indicated by the arrows, the valves d and d' remaining substantially stationary, and the pistons make their return-stroke in the same manner that they made their forward stroke. Thus it will be seen that at the beginning of the stroke, when there would naturally be an excess of power, I apply an extra resistance, and toward the end of the stroke, when the steam has expanded somewhat and there is a deficiency of power, I apply an extra force in aid of the engine. It will also be seen that I attain a high degree of expansion, as the steam from the receiver is expanded in E and E' from the point of cut-off to the end of the stroke, and is then further expanded on the return-stroke into F and F' .

I have not thought it necessary to show or describe the valve-operating mechanism or the pumping mechanism, as the ordinary mechanician skilled in this art will readily adopt such appliances as may be suitable, and will also make such modifications and adaptations of what I have shown and described as may seem desirable in the particular case he has in view.

On first starting the engine after it has been idle for a time, it is desirable to admit a por-

tion of steam to the receiver, so as to have a supply there to start with. This may best be done by admitting a portion of steam direct from the boiler by a pipe provided for that purpose.

What I claim as new, and desire to secure by Letters Patent, is—

1. The method of operating and equalizing the power of an engine which uses steam expansively, by causing steam under initial pressure acting in a cylinder to re-enforce the engine during the latter parts of its stroke, exhausting said steam into a receiver, and drawing steam from said receiver to drive the engine, substantially as set forth. 75
2. The method of operating and equalizing the power of an engine which uses steam expansively, by causing steam under initial pressure acting in a cylinder to oppose the motion of the engine during the first parts of its stroke, exhausting said steam into a receiver, and drawing steam from said receiver to drive the engine, substantially as set forth. 80
3. The method of equalizing the power of an engine which uses steam expansively, consisting in causing steam under initial pressure acting in a cylinder to oppose the motion of the engine during the first portions of its stroke, causing steam under initial pressure acting in a cylinder to favor the motion of the engine during the latter portions of its stroke, exhausting the steam thus used into a receiver, causing steam from the receiver to favor the motion of the engine during the first portions of its stroke, and causing steam from the receiver to oppose the motion of the engine during the latter portions of its stroke, substantially as set forth. 90

4. The method of operating and equalizing the power of an engine which uses steam expansively, consisting in causing steam under initial pressure acting in a cylinder to oppose the motion of the engine during the first portions of the stroke, causing steam under initial pressure acting in a cylinder to favor the motion of the engine during the latter portions of its stroke, exhausting the steam thus used into a receiver, and drawing steam from said receiver to drive the engine, substantially as set forth. 105

5. The method of equalizing the power of an engine which uses steam expansively, consisting in causing a portion of steam under less than initial pressure acting in a cylinder to favor the motion of the engine during the first parts of its stroke, and causing a portion of steam under initial pressure acting in a cylinder to favor the motion of the engine during the latter parts of its stroke, substantially as set forth. 120

6. The method of operating and equalizing the power of an engine which uses steam expansively, consisting in employing three cylinders and a receiver, one of said cylinders being larger than the others, admitting steam from the receiver behind the smaller pistons during the first parts of the stroke and in 130

front of one of them during the latter parts thereof, admitting steam under initial pressure in front of one of the smaller pistons during the first parts of the stroke and behind one of them during the latter parts thereof, and exhausting said steam at the proper time into the receiver, and expanding the steam remaining in front of one of the

smaller pistons from a previous stroke into the space behind the larger piston, substantially as set forth.
